(Cl. D48—27)

To all whom it may concern:

Be it known that I, Joseph C. Clark, a citizen of the United States, residing in Merchantville, county of Camden, State of New Jersey, have invented a new, original, and ornamental Design for an Electric Cigarette Lighter or the like, of which the following is a specification, reference being had to the accompanying drawing, forming part thereof.

In the drawing:

Fig. 1 represents a front elevational view of an electric cigarette lighter or the like, showing my new design;

Fig. 2 represents a rear elevational view thereof; Fig. 3 represents a top plan thereof;

Fig. 4 represents a left side elevational view thereof; and

Fig. 5 represents a right side elevational view thereof.

I claim:

The ornamental design for an electric cigarette lighter or the like, as shown.

JOSEPH C. CLARK.
